UNITED STATES PATENT OFFICE.

HENRY MUTCHNIK AND HYMAN RUDOW, OF BALTIMORE, MARYLAND.

WINDOW.

1,297,892.

Specification of Letters Patent.

Patented Mar. 18, 1919.

Application filed March 30, 1918. Serial No. 225,746.

To all whom it may concern:

Be it known that we, HENRY MUTCHNIK and HYMAN Rudow, citizens of Austria and Russia, respectively, residing at Baltimore,

5 State of Maryland, have invented new and useful Improvements in Windows, of which the following is a specification.

This invention relates to improvements in windows and especially with reference to 10 the provision of hanging stiles arranged for vertical sliding movement in a window casing and in which a window sash is pivotally mounted so that the sash can be turned on its pivots and arranged in an inclined position, for purposes of ventilation, or can be 15 turned down to a horizontal position to facilitate the washing of the outside of the panes; one object of the invention being to effect improvements in the construction of the 20 hanging stiles; another object is to provide improved means for counter-balancing the weight of the sash and the hanging stiles and supporting the sash and hanging stiles in any desired position; another object is to 25 provide improved means for adjustably holding the sash in inclined position and to permit the sash to be turned down to a horizontal position.

The invention consists in the construction, 30 combination and arrangement of devices hereinafter described and claimed.

In the accompanying drawings:

Figure 1 is a perspective view of a portion of a window sash and a hanging stile 35 constructed and arranged in accordance with our invention and provided with our improved adjusting links and sash balances, and showing the sash in inclined position.

Fig. 2 is a vertical sectional view.

Fig. 3 is a transverse sectional view.

Figs. 4, 5 and 6 are detailed views.

In the embodiment of our invention we provide a pair of hanging stiles 1 for each window sash 2, the stiles being arranged on opposite sides of the window sash and being arranged also for vertical sliding movement in the usual grooves of the window casing 3 formed between the parting strip 5 and the strips 4 spaced therefrom. The sash is pivoted between the lower ends of the hanging stiles, the pivots 6 being horizontally arranged and projecting outwardly from metal inlaid plates 7 which are secured in rabbets in the sides of the sash.

55 Thereby the sash is pivotally mounted between the hanging stiles so that the sash can

be arranged either in a vertical position, in a horizontal position or in an inclined position as may be desired.

Each hanging stile is hollow and is provided with a chamber 8 which is open on the outer side and which is nearly coextensive in length and width with the stile. The inner wall 9 of each hanging stile is also preferably provided with openings 10 as here

shown. To balance the sash and the hanging stiles we provide each hanging stile with drums, 60 springs to turn the drums and cords, each of which has one end attached to one of the 65 drums and the other end secured to a bar 11 which is arranged in the chamber of the hanging stile and is secured as by means of a screw 12 or the like to one side of the window casing. The drum 13 is arranged near 70 the upper end of the stile, in the chamber thereof, and is mounted for rotation on a suitable supporting axle 14 and is associated with a coiled spring 15 one end of which is attached to the drum, the other end of the 75 spring being attached to the axle. The other drum 16 is arranged near the lower end of the hanging stile, in the chamber thereof, is mounted to turn on the axle 17 and is associated with a spring 18 which is 80 wound reversely to the spring 15 so that the 85 springs serve to turn their respective drums in reverse directions. The cords 19, 20 are in practice, flat tapes and are respectively connected to the drums 13, 16 and wound 90 reversely thereon. Hence the springs cause the drums to counteract each other and as the stiles are raised or lowered together with the sash the drum in one end of each hanging stile winds up its cord while the drum 95 in the opposite end of the hanging stile unwinds its cord and the sash and hanging stiles are maintained at any desired elevation, as will be understood. The drums 13 and 16 and their springs and tapes serve in 100 effect as checks for cushioning retarders. Thus when the stiles and the sash therein are moved downwardly the drum 16 and its appurtenances will perform the cushioning function, while when the stiles and sash are 105 moved upwardly the checking or cushioning function will be performed by the drum 13 and its appurtenances. From this it follows that the drum 13 and appurtenances cushion the stiles and sash when the same are 110 violently moved upwardly, and the drum 16 and appurtenances will perform the same

function when the stiles and sash are violently moved downwardly.

To adjustably hold the sash in inclined position and to permit the sash to be turned to a horizontal position, so that the side of the panes can be readily washed, we provide a pair of links 21, 22 which are respectively pivotally connected to one of the hanging stiles as at 23 and to one side of the sash as at 24. The stiles are provided at their outer sides with inwardly extending flanges 25 against which the sash closes when the sash is turned to its usual vertical position; said flanges serving as weather strips and to close the cracks between the sash and the hanging stiles. The pivot 23 of the link 21 is in a lug 36 with which one of the flanges 25 is provided. Said link 21 has a longitudinal slot 28 in the lower side of which are notches 29 and near the outer end of which is an enlarged opening 30. The link 22 has a headed stud 31 which projects from one side thereof near the outer end of said link, said headed stud being slidable in the slot of the link 21 and being adapted to be engaged with any one of the notches in said link to hold the sash in any desired inclined adjusted position. The opening or broadened portion of the slot serves to clear the head of the stud and to enable the stud to be entirely disconnected from the link 21 and thus enable the sash to be turned downwardly to a horizontal position. When the sash is in vertical position the links are arranged side by side and in a recess 33 in one side of the sash.

To secure the sash in normal, vertical position we provide a fastener 34 which is hinged or pivoted to the inner side of one of

the hanging stiles near the upper end thereof, as at 35 and which has a stud 36' which may be engaged in a recess 37 in the top of the sash.

While we have herein shown and described a preferred form of our invention, we would have it understood that changes may be made in the form, proportion and construction of the several parts, without departing from the spirit of our invention and within the scope of the appended claims.

Having thus described our invention, we claim:—

1. In a window of the class described, a casing, a hanging stile arranged for vertical sliding movement in the casing and provided with a chamber in the side next the casing, a drum carried by the stile and mounted for rotation, a spring to turn the drum in one direction and a cord having one end connected to the drum and winding thereon by the action of the spring, the other end of the cord being fastened to the casing.

2. In a window of the class described, a casing, a hanging stile arranged for vertical sliding movement in the casing and provided with a chamber in the side next the casing, a pair of drums carried by the stile and mounted in said chamber for rotation, springs for the respective drums to turn the drums in reverse directions and cables attached to and reversely wound on the drums, and each having one end fastened to the casing.

In testimony whereof we affix our signatures.

HENRY MUTCHEK.
HYMAN RUDOW.
